UNITED STATES PATENT OFFICE.

JOHN M. KELLEY, OF ROCHESTER, NEW YORK, ASSIGNOR, BY MESNE ASSIGNMENTS, TO
THE PROTANE CORPORATION (1926).

PROCESS AND APPARATUS FOR BURNING LIQUID FUEL.

Application filed June 18, 1923. Serial No. 645,945.

The present invention relates to a process of burning liquid hydrocarbon fuels and is particularly advantageous with fuels having a dry end point not in excess of 150° F. and an initial boiling point of approximately 45° F. or lower and which will not develop a pressure in excess of 50 pounds per square inch at 100° F., and to a burner used in such process. An object of the invention is to make it possible to utilize some of the products of casinghead gas which have heretofore been deleterious to gasoline made from casinghead gas or have been waste products. Another object of the invention is to store such liquid, deliver it in liquid form to a point of use, expand it to a gas by its release and burn the fuel in its expanded gaseous form. Another object of the invention is to make it possible to employ a small flame such as produced from a match to prevent the congealing of the moisture of the atmosphere as the gas issues from a small orifice and to utilize such flame for igniting the burner, after the gas has been properly mixed with air. Another object of the invention is to provide for the collecting of wet gas which may escape from the orifice in a chamber so situated with reference to the jet openings of the burner that the wet gas will evaporate and be burned through the jet openings. Still another object of the invention is to provide a fuel delivery device in which the orifice, which discharges into the mixing chamber of the burner, is provided in an expansion chamber whose walls adjacent to the orifice are of high heat conductivity and are so situated that jets from the burner will play thereon, in order that the flame from a match applied to the walls of the expansion chamber adjacent to the orifice will also ignite the burner and cause the latter to maintain the walls of the orifice in a warm condition during the burning of the gas. Still another object of the invention is to use in connection with a burner for burning this liquid fuel, a fuel delivery device in which the expansion chamber has a tapered discharge orifice and an inlet opening, the inlet opening being controlled by a valve which has a stem extending therefrom and provided with a tapered portion operating in the tapered discharge orifice in order to regulate the flow from the latter.

To these and other ends, the invention consists of certain parts and combinations of parts, all of which will be hereinafter de-

scribed; the novel features being pointed out in the appended claims.

In the drawings:

Fig. 1 is a sectional view through a container constructed in accordance with this invention;

Fig. 2 is an enlarged sectional view showing the dispensing apparatus connected with the container;

Fig. 3 is a similar view of the container outlet and filling bushing;

Fig. 4 is a section on the line 4—4, Fig. 2;

Fig. 5 is a perspective view of a gas stove equipped with the present invention;

Fig. 6 is a plan view partially in section of a burner constructed in accordance with this invention;

Fig. 7 is a section on the line 7—7, Fig. 6; and

Fig. 8 is an enlarged section showing the connection between the fuel line and the fuel delivery device.

Gas escaping from the oil sands in the production of crude oil is known to the trade as casing head gas and as compared with commercial natural gas, it is from two to three times heavier and has a B. t. u. value per cubic foot at standard conditions of from 1500 to 2500 as compared with commercial natural gas having a B. t. u. value of from 800 to 1000. The commercial composition of casing head gas is represented by the following compounds:

Methane CH_4 , ethane C_2H_6 , propane C_3H_8 , butane C_4H_{10} , pentane C_5H_{12} , hexane C_6H_{14} , heptane C_7H_{16} .

These belong to the same chemical family but with different physical characteristics. The first compound is a gas about one-half as heavy as air and requiring about the same pressure and temperature as air to liquefy. The second compound is also a gas at ordinary temperatures and pressures, requiring about seven hundred pound pressure and a temperature of 40° Fahrenheit to liquefy. The third compound is a gas of ordinary pressure and temperature but liquefies at 250 pounds at a temperature of 63° F. The fourth compound is a liquid at atmospheric pressure at a temperature of 32° F. The fifth compound is a liquid at 60° F., at atmospheric pressure, and forms one of the lighter fraction of commercial gasoline. The sixth and seventh products are the main constituents of commercial gasoline.

Heretofore it has been common practice to utilize this casinghead gas in the production of commercial gasoline, but owing to the inclusion therein of lighter fractions, this gasoline, when produced, has a high vapor tension and is dangerous and therefore impossible to use commercially in that form, thus making it necessary to weather this gas in order to permit the lighter vapors to pass off in the atmosphere. These lighter vapors have not been heretofore generally utilized and have therefore been waste products. The lightest of these fractions have been used to some extent for producing what is known commercially as "liquefied" gas. This liquefied gas, however, has a very low initial boiling point, in some instances -80° F., and develops an exceedingly high pressure at normal atmospheres 300 pounds at 70° F. The exceedingly high pressure developed by such liquefied gas requires the use of exceedingly heavy and strong containers, which makes the general use of the product prohibitive. Furthermore, in the use of such liquefied gas, it passes from the container in the form of gas, so that there is a gradual increase in the density of the gas given off which necessitates an adjustment of the air mixer of the burner in order to maintain a uniform flame, the low boiling point of such gas not permitting its being used in any other manner.

According to this invention a liquid fuel is preferably obtained by known processes from intermediate products of the casinghead gas which will not develop a pressure in excess of 50 pounds per square inch at 100° F. and which has a dry end point not in excess of 150° F. and an initial boiling point of approximately 45° F. or lower. These intermediate products not only are a disadvantage to commercial gasoline made from casinghead gas but are also a disadvantage to "liquefied gas" hereinbefore mentioned, as they tend in one to increase the vapor tension and in the other to leave a non-consumable residue in the containers. The liquid hydrocarbon obtained from these intermediate fractions may be readily transported in light and inexpensive containers. The most desirable commercial product does not develop a pressure in excess of 20 pounds at 100° F., thus making it possible to transport the product under the rules and regulations of the Interstate Commerce Commission with reference to the transporting of dangerous articles other than explosives. Furthermore by having an initial boiling point of approximately 45° F. or lower it is possible to draw the liquid fuel from the bottom of the container under the pressure generated in the container by the product and to conduct this liquid fuel to the burner through a capillary like tube, the liquid fuel being gasified by its release at the burner and by the use of slight

warmth from the burner neutralizing the absorption of heat on the expansion of the fuel to a gas.

The form of container which may be employed in connection with this liquid fuel is illustrated in Figs. 1 and 2, in which 1 indicates the container proper having a head formed with a depressed portion 1^a provided with a screw threaded opening 2, in which is fitted an externally threaded bushing 3. The bushing is formed with a passageway comprising a chamber 4 and an internally threaded bore 5 separated by a restricted portion 6 in which an opening 7 is formed. In the chamber 4, a valve is arranged preferably in the form of a ball 8 to seat against the restricted portion 6 in order to close the opening 7, there being also arranged in the chamber 4, a helical spring 9 which bears against the ball to hold it against the seat. With the chamber 4 a filling tube and dip pipe 10 connects preferably through a collar 11 which is brazed on the end of the tube in slightly spaced relation to the latter and is externally threaded so that this collar may be engaged with internally threaded walls 12 formed in the chamber 4. The projecting end of the tube acts as a guide for the spring 9 and is notched at 13 so that in the event the ball should seat against the same, it would not close off the flow of gas. It is apparent that this spring with the internal pressure in the tank which may be as high as 50 pounds per square inch, will maintain the ball against the restricted portion 6 and prevent the escape of gas.

To provide against accidental displacement of the valve 8 from its seat in shipment, an externally threaded plug 14 may engage the internally threaded walls of the bore 5 and may have a tapered end 15 for engaging a similarly formed wall 16 on the bushing at the inner end of the bore 5, thus providing a tight fit which will prevent the accidental escape of any gas from the container.

In order to provide a tight joint between the bushing 3 and the container, the bushing has a projecting portion 17 on the exterior of the container, and the face of this projecting portion opposed to the head of the container has a groove in which a packing 18 is arranged, this packing cooperating with an annular bead or rib 19 formed on the adjacent head of the container. To provide a vent in order to enable the container to be filled or for the purpose of controlling the pressure within the container, a venting means is employed comprising a port or passageway 20 leading to a valve seat 21 against which seats a ball valve 22 held in position by a socket plug 23, the loosening of which permits the ball to move away from its seat and to open up a passage 24 to the exterior of the container. The inner end of this passageway is spaced from the adjacent head of

130

the container as it is desirable to leave a space between the head and the liquid in order to prevent the complete filling of the container and avoid consequent excess pressure in the 5 container.

With the end in view of drawing the liquid from the container, a dispensing means is provided comprising a head 25 provided with an inlet 26 to which a connector 27 is secured 10 by screw thread 28. This connector has a tapered end 29 adapted to seat against the seat 16 of the bushing 3 when the plug 14 is removed. Also provided on the connector is a surrounding shoulder or abutment 30. 15 With this shoulder or abutment an externally threaded collar 31 engages, this collar being insertable in the bore 5 to cooperate with the internally threaded walls thereof, so as to force the tapered end 29 against the seat 16, 20 in order to form a tight joint with the bushing, thus making the connection interchangeable with other containers and dispensing with any other packing material. In order that the valve 8 may be opened, a valve operating 25 plunger 32 is mounted on the dispensing means and extends through the connector 27 and also through the head 25, its upper end being screw threaded at 33 and engaging in a screw threaded sleeve 34 which also acts 30 to firmly hold a packing 35 about the stem 32. It is apparent that the turning of the handle 36 will effect the longitudinal movement of the stem, the lowering of the stem effecting the movement of the valve 8 away from its 35 seat to permit the liquid to flow from the container, and the raising of the stem permitting the valve 8 to close. This stem is preferably only operated after the head 25 is connected to the container and it is apparent that as 40 the head is disconnected, the valve will automatically close.

The main flow from the container is controlled by a valve comprising a casing 37 fitting in the head 25 and having an inlet 38 45 communicating with the head and an outlet 39 connecting with the service line, a reciprocating valve 40 controlling the flow through the valve casing 37 and being operated through a handle 41. A pressure gauge 42 50 connects with the head 25 and indicates the pressure in the container. While at ordinary temperatures and elevations the container will have an internal pressure sufficient to cause the flow of the liquid therefrom to the 55 point of use, it is desirable when the atmospheric temperature drops below the initial boiling point of the liquid or fails to produce this pressure in the container, there is provided a valve connecting member 43 secured to the member 25 and having a nipple 44 to which an air pump may be connected. This nipple leads to a passageway 45 controlled by a ball valve 46 and also by a reciprocating valve 47. The opening of the reciprocating valve exposes the ball valve 46 which

under normal conditions will be held to its seat 48 by internal pressure, but when air is forced into the passageway 45 the valve 46 will be displaced and such air under pressure will pass into the container above the liquid. 70

A burner which may be employed for burning this fuel comprises a fuel delivery device embodying an elongated narrow expansion chamber 50 formed by a pliable tube 51 of material of high heat conductivity such as copper and connected at one end to a head 52 preferably by forming a tapered end 53 on one end of a tube adjacent a shoulder 54 and holding said tapered end to a tapered seat 55 on the head 52 by means of a nut 56 75 which engages the shoulder 54 and forces the tapered end 53 firmly to the seat 55. The head 52 has a laterally projecting portion 57 in which a connector 58, screw threaded at opposite ends, is adapted to be secured, this connector having the service pipe 49 secured thereto by a nut 59 which forces the tapered end on the pipe 49 firmly against the connector 58. This service pipe 49 is what might be called capillary tubing in that the opening therethrough is very small, say about three thirty seconds of an inch, and readily conducts the proper amount of fuel to the burner and, at the same time, does not require a heavy pressure in the container. In 80 the casing 52 a valve seat 60 is provided with which cooperates the tapered portion 61 of a valve member 62 which is externally threaded at 63 and is operable by means of a handle 64 on the exterior of the casing. 100 This valve member has a pliable stem 65 extending therefrom through the expansion chamber 51 and this stem is surrounded by a closely fitting helical coil 66 of tape stock which causes the liquid to travel in a helical path about the stem 65 during its expansion. 105 The end of the expansion chamber is closed preferably by a plug 67 which has a tapered orifice 68 therethrough, and in this orifice the tapered end 69 of the stem 65 projects. 110 It is apparent that after the liquid has expanded in the expansion chamber, and there is the heat absorption of the expansion from a liquid to a gas, the fuel issues from the orifice 68 as a gas under high pressure which tends to congeal moisture in the atmosphere at the orifice, and the amount of this pressure is determined by the adjustment of the tapered end 69 of the stem 65. After issuing from the orifice, the gas enters the mixing 115 chamber 70 in the bottom of which is formed adjacent the end of the expansion chamber, an air inlet passage 71, the area of which is controlled by a valve 72 preferably in the form of an externally threaded portion 73 120 formed with lateral ports 74 and adjustable within the air inlet passage 71, the end of the air inlet passage operating over the air inlet ports 74 to control the amount of air passing 125 into the mixing chamber. 130

The mixing chamber is of novel construction and is provided with a return bend 75, the chamber being provided with a collecting pocket 76 lying beneath an outlet 77 to the jet openings of the burner. In this instance, the jet openings are formed in an annular ring 78 which lies in an annular groove 79 in a plate or member 80 in which the opening 77 is formed. Closing the annulus 78 is a 10 plate 81 and this plate together with the annulus 78 is held to the casting by a bolt 82 which passes through the plate 81 and the opening 77 and is anchored in an opening 83 in the bottom wall of the pocket 76. The 15 plate 80 is provided at one side with a series of parallel grooves or recesses 84 which intersect the plane of the expansion chamber 51 near one end of the latter. The annulus 78 has jet openings 85 formed therein, above 20 the plane of the expansion chamber, so that an annular flame is provided about the top plate 81. The top plate projects beyond the annulus 78 and in this way protects the jet openings against clogging due to spilling of 25 matter thereon, such as results from the overflow of vessels, etc. The burner as a whole may be supported by a cross bar 86 which is anchored by a bolt 87 to the underside of the casting in which the mixing chamber 75 is 30 formed. This cross bar is so positioned that it underlies the air valve 72 and prevents the latter becoming displaced from the air opening.

In carrying out this invention the containers are preferably filled with the liquid fuel as described at suitable stations and are shipped to the consumers, the fuel being in a liquid state and the containers being of a size corresponding to the demand of the user. 35 These containers are then connected to the apparatus employed by the user, the plug 14 being removed from the bushing 3 of the container and the dispensing head 25 having its connection 27 connected with the bushing 45 through the sleeve 31. Thereafter, the valve plunger 32 is operated to permit the liquid fuel to flow from the container under the pressure therein by way of the dip pipe 10 into the service line 49 to the fuel consuming 50 device.

If the fuel consuming device employed is in the form of a burner, such as herein illustrated, the user warms the expansion chamber 51 with an ordinary match and before the match is consumed, and, while yet 55 playing upon the expansion chamber, turns the valve operating member 64 to permit liquid fuel to flow from the service pipe 49 into the expansion chamber 51 about the stem 65. In passing into this expansion 60 chamber, the liquid fuel expands rapidly and turns into a gas, which issues under pressure through the orifice 68, the size of which is adjusted to correspond with the pressure of 65 the gas, which varies with the temperature of

the atmosphere. While the valve 62 and the needle 69 work together, nevertheless the main control is established by the needle as the pressure built upon the expansion chamber will hold back the flow of liquid fuel by 70 way of the valve 62. As the gas issues from the nozzle or orifice 68, it projects with force over the air inlet into the mixing chamber and returns forwardly to pass through the jet openings 85 by way of the opening 77. At 75 the same time, some of the gas passes through the jet openings 84 and is ignited by the flame of the match playing upon the expansion chamber. The fuel having such a low boiling point requires but a small amount of warmth 80 "to turn it over" or convert it into dry gas and at the temperatures of ordinary use flashes into gas upon its release. As this liquid fuel is under pressure, has a low boiling point and is extremely volatile, it would set 85 up a freezing condition when issuing from a small orifice and this burner overcomes this objection by warming the expansion chamber adjacent the orifice 68 an amount neutralizing the heat absorption of the fuel in its expansion from a liquid to a gas and sufficient to prevent this freezing action during the ignition of the burner, and this is maintained, while the burner is in use through the small jets issuing from the orifices 84. Should any 90 wet gas pass from the orifice 68 it will be projected with force across the air opening and into the mixing chamber, where it will flow to the collecting pocket 76. This might occur should the operator turn on the valve 100 before sufficiently warming the expansion chamber but as soon as the match is applied the gas will immediately light and will warm the expansion chamber, and, at the same time, hold the wet portion in the pocket to be consumed by the burner without any danger of 105 accident due to dripping such as is common in ordinary liquid fuel burners. As soon as the burner is lighted, the warming of the expansion chamber prevents any flow of wet 110 gas. The form of the gas is such that it carries no heavy matter and therefore leaves no carbon deposits in the expansion chamber which would tend to clog the same or the orifice 68.

From the foregoing it will be seen that there has been provided a process and an apparatus for burning liquid hydrocarbons of the methane series having a low boiling point. This apparatus embodies a container in which the fuel is held in a liquid state under a low pressure and having a valve in a dip tube leading from it. Said valve normally occupies a closed position and is mounted in a removable bushing to which the dip tube connects. This bushing has a removable plug which seats against the wall of the bushing to close effectively the outlet from the dip tube independently of the valve. A vent is also provided in the bushing for controlling 115 120 125 130

the pressure in the container. A dispensing head detachably connects with the bushing and forms a tight connection therewith. This dispensing head carries means for opening the container valve so that the fuel may be fed therefrom under pressure. It also carries means through which air may be introduced into the container above the liquid, and a pressure gauge through which the pressure in the container may be obtained. A valve on the head controls the flow of liquid fuel to a suitable fuel consuming device. The fuel consuming device is in the form of a burner which has an expansion chamber adapted to be warmed by a match or other small flame so as to insure the passage of the gas from a small orifice into the mixing chamber, the match or other device employed for warming the expansion chamber being without any further movement on the part of the user utilized for igniting the burner when the gas issues from the same. The burner has a mixing chamber beyond the air inlet so formed as to collect the wet fuel in such a position that such fuel will be consumed by the burner after the ignition of the latter. The burner has jet openings so arranged as to play upon the expansion chamber after the burner has been ignited to neutralize the heat absorption of the fuel in its expansion from a liquid to a gas.

What I claim as my invention and desire to secure by Letters Patent is:

1. The process which consists in expanding into a chamber a liquid hydrocarbon fuel having a dry end point not in excess of 150° F. and an initial boiling point of approximately 45° F. or lower and which will not develop a pressure in excess of 50 pounds at 100° F., discharging the expanded fluid from the chamber and permitting it to further expand, applying sufficient heat at the point of escape from the chamber to prevent congealing of the moisture of the atmosphere at the orifice, mixing the expanded fluid with air, and conducting a portion of the mixture to the heated area for ignition.
2. A burner for liquid hydrocarbons of the class described, comprising a member formed with a central opening and grooves in the top of said member, a ring resting on said member about the central opening, extending across the grooves and formed with jet openings, a plate secured to the ring to close the latter, a mixing chamber in the form of a return bend having one arm extending under the member and formed with a pocket below the central opening of said member and having the other arm provided with an air inlet, and a fuel mixing device formed with an expansion chamber having an orifice discharging into the mixing chamber, the walls of the expansion chamber adjacent the orifice being of high heat conductivity and being adjacent the grooves in the top of the member so that a flame from a small flame producing device will warm the walls of the orifice to prevent the congealing of the moisture of the atmosphere due to the rapid expansion and will ignite the gas as it passes from the grooves so that the walls of the expansion chamber adjacent the orifice are warmed by the jet openings during the burning of the burner.
3. A burner for liquid hydrocarbon fuels of the class described, comprising a member formed with a central opening and grooves in the top of said member, a ring resting on said member above the central opening, extending across the groove, a plate secured to the ring to close the latter, a mixing chamber in the form of a return bend having one arm extending under the member and formed with a pocket below the central opening of said member and having the other arm provided with an air inlet, a fuel mixing device formed with an expansion chamber having an orifice discharging into the mixing chamber, the walls of the expansion chamber adjacent the orifice being of high heat conductivity and being adjacent the grooves in the top of the member so that a flame from a small flame producing device will warm the walls of the orifice to prevent the congealing of the moisture of the atmosphere due to the rapid expansion and will ignite the gas as it passes from the grooves so that the walls of the expansion chamber adjacent the orifice are warmed by the jet openings during the burning of the burner.
4. An apparatus of the class described comprising a capillary service tube, a delivery device connected with said capillary service tube and having an expansion chamber with a small orifice, the walls of the chamber adjacent the orifice being formed of material of high heat conductivity, means for controlling the flow through said orifice, a mixing chamber into which the gas from the orifice is expanded having a pocket in which unvaporized fractions of the gas may be collected and formed with a restricted discharge constructed to cause said heavy fractions to be picked up by the flow of gas through the mixing chamber, and a burner having jet openings through which gas from the mixing chamber is burned, some of said jet openings being arranged in close proximity to the expansion chamber.
5. The method of generating heat, which consists in storing a liquid hydrocarbon fuel having a dry point not in excess of 150° F. and an initial boiling point at least as low as 45° F. or lower and which will generate a pressure not in excess of 50 pounds at 100° F. in an enclosed receptacle at atmospheric temperatures, conveying the fuel by pressure so created and in liquid form to a point of

application remote from the stored liquid, releasing the liquid at the point of application from pressure and permitting it to expand as a gas and burning the gas.

- 5   6. The method of generating heat, which consists in storing a liquid hydrocarbon fuel having a dry point not in excess of 150° F. and an initial boiling point at least as low as 45° F. or lower and which will generate a
- 10 pressure not in excess of 50 pounds at 100° F. in an enclosed receptacle at atmospheric temperatures, conveying the fuel by pressure so created and in liquid form to a point of application remote from the stored liquid, releasing the liquid at the point of application from pressure and permitting it to expand as a gas, applying heat to the expanding fluid
- 15

to compensate for the cooling effect due to the expansion, and burning the gas.

7. The method of generating heat which consists in confining a liquid hydrocarbon having a volatility gasifying on release to the atmosphere, delivering the fuel as a liquid from a point of storage to a point of use remote from the point of storage, releasing the fuel adjacent to the point of use and permitting its expansion as a gas, subsequently supplying the heat absorbed by the fuel in its expansion from the liquid to a gas, burning the expanded fuel in its gaseous state, and utilizing heat from the burning gas to supply heat absorbed by the fuel in expanding to a gas.

JOHN M. KELLEY.
